UNITED STATES PATENT OFFICE.

CARL H. GRIESE, OF CLEVELAND, OHIO.

MEANS FOR VENTILATING BUILDINGS.

SPECIFICATION forming part of Letters Patent No. 341,328, dated May 4, 1886.

Application filed June 1, 1885. Serial No. 167,213. (No model.)

To all whom it may concern:

Be it known that I, CARL H. GRIESE, of Cleveland, in the county of Cuyahoga and State of Ohio, have invented certain new and useful 5 Improvements in Heating and Ventilating; and I do hereby declare the following to be a full, clear, and exact description of the invention, such as will enable others skilled in the art to which it pertains to make and use the 10 same.

My invention relates to an improved system of heating and ventilating, adapted more especially to school-buildings and other buildings of similar construction; and it consists, 15 essentially, in the arrangement of radiators, registers, induction and eduction air-ducts, air-chambers, and ventilating-chimneys, hereinafter more fully described, and pointed out in the claims.

20 In the accompanying drawings is illustrated my improved system, a portion only of the building being shown.

Figure 1 is an elevation in section showing the location of the hall-registers. Fig. 2 is an 25 elevation in section showing the location of radiators, cold-air ducts, and ventilating-ducts, the latter located between the floor-joists. Fig. 3 is a plan view. Fig. 4 is an elevation showing externally the air-duct 30 under the window for supplying air to a radiator. Fig. 5 is a transverse section on the line xx , Fig. 4.

A represents radiators that are of the vertical tubular variety, with openings through 35 the base for the passage of air up among the tubes. The radiators set upon the floor, and are respectively inclosed by a casing, B, metal-lined, with a register, b , on top, preferably of the rolling-slot variety. This casing incloses 40 a reservoir or hot-air chamber, B', and prevents a direct lateral radiation from the radiator, by reason of which the temperature is not materially different in the vicinity of the radiators from that of other portions of the 45 room. Air is supplied from the outside of the building through the ducts a , located directly under the window, and leading down under and up through the floor, and discharging under the radiator, as shown in Fig. 5. 50 These ducts should be provided with dampers (not shown) for controlling the draft. From

the fact that these air-ducts receive their supply some distance from the ground they are free from many of the objectionable features of underground ducts receiving air near the 55 grade-line that are therefore liable to draw in dust, or malarious or other noxious exhalations of the ground. The outer opening of the duct is covered with the screen or lattice work a' , usually of some ornamental pattern. 60

The air passes through these ducts and up through the radiators, and is discharged in a heated condition first into the chamber B', and from thence through the register b in an upward direction into the room. This heated 65 air of course rises to the ceiling, where, in the absence of other agencies, it would stagnate, to avoid which lateral currents of cold air are admitted from the ducts C through the registers c , located near the ceiling. These lateral 70 currents commingle with the heated air, set the mass in motion, causing it to circulate freely, and by reducing the temperature causes it to be precipitated to the floor, to make room for the fresh supply constantly entering from 75 the registers b and c .

D are registers set in the floor at various parts of the room, and lead, respectively, to the ducts d , that conduct the foul air to the chambers E, from which it passes through the 80 flues e to the ventilating-chimneys F. The ducts d are arranged between the floor-joists and lined with tin. The chambers E are arranged over the closets E', the ceilings of which are depressed for this purpose some distance 85 below the line of the ceiling in the larger rooms. The chimneys F are of ample size in cross-section, and are located in the central portions of the building. The draft in these chimneys is relied upon to carry off the foul 90 air that is discharged from the ducts d and for the hall-registers H, that also discharge into the chambers E when practicable, or otherwise into suitable ducts leading to the chimneys F. As the force of the draft depends 95 on keeping the air in the chimneys uniformly at a considerably higher temperature than that of the external air, the location of these stacks in the central portion of the building, where they are not exposed to the wind and the extremes of cold, is a matter of great importance. 100 One of these ventilating-chimneys can usually

be heated by the smoke-pipe from the boiler, and the waste heat of the boiler-room may be utilized for this purpose. The other chimney may be warmed by stoves, coils of steam-pipe, 5 or both. With this system of heating and ventilating a constant and abundant supply of fresh air is always had, and the foul air is not allowed to accumulate, but is continually being drawn from the rooms, and the rooms are 10 heated evenly throughout.

I am aware that it is old in systems of ventilating to take air in near the ceiling and discharge it near the floor by means of an exit stack or flue. I am also aware that it is old 15 to heat and ventilate rooms by drawing fresh air in through a chamber containing a radiator. I therefore do not claim either of these features separately.

What I claim is—

20 1. The combination, with a room and a radiator, of an inlet-duct at the lower portion of the room communicating with the radiator-chamber, an inlet at the upper portion of the

room to admit cool air to mingle with the fresh warm air rising from the radiator-chamber, a 25 number of outlets distributed over the floor, and a ventilating flue or chimney with which the outlet-openings in the floor connect, substantially as and for the purposes set forth.

2. The combination of a room having a radiator provided with a jacket through which fresh-heated air is drawn upwardly, an inlet at the upper part of the room through which fresh air is drawn downwardly to mingle with the fresh warm air, air-outlet ducts distributed 35 in the floor, and a suction device with which the ducts connect for compelling the mingled air to pass out of the room in regular currents, substantially as set forth.

In testimony whereof I sign this specification, in the presence of two witnesses, this 15th day of May, 1885.

CARL H. GRIESE.
